TOWER JACKING STRUCTURE DRIVE

Erwin A. Campbell, Wexford, Pa., assignor to Lee C. Moore Corporation, Pittsburgh, Pa., a corporation of Pennsylvania

Application October 7, 1950, Serial No. 188,971

4 Claims. (Cl. 254—92)

1

This invention relates to tower jacking structures, such as shown in my copending application, Serial No. 124,665, now Patent No. 2,530,807, dated November 24, 1950, and more particularly to a driving mechanism for such a structure.

It is among the objects of this invention to provide a tower jacking structure drive in which all jacks can be raised simultaneously by a single motor-operated driving unit, and in which the driving mechanism is easily attached to and removed from the jacking structure.

In accordance with this invention, a jacking structure surrounds a multiple leg tower and has a separate gear driven screw jack for each tower leg. Generally, there are four tower legs, and therefore four jacks. A substantially horizontal drive shaft is provided for each jack gear drive, each shaft extending toward the center of the jacking structure. Operatively connected to the inner ends of all of the drive shafts is a gear reduction unit which is disposed near the center of the jacking structure. This unit and the motor which drives it may be supported by a frame suspended from the bottom of the jacking structure. The gear reduction unit preferably includes a worm that is journaled on a vertical axis at the center of a gear housing, and worm gears journaled on horizontal axes in the housing and meshing with the worm at uniformly spaced intervals around it. The worm gears may be mounted on stub shafts which are connected by drive shafts extending diagonally of the jacking structure to the different jack gear drives.

The preferred embodiment of the invention is illustrated in the accompanying drawings, in which Fig. 1 is a fragmentary side view of a skeleton tower with the jacking structure surrounding it and with the tower elevated several inches; Fig. 2 is a horizontal section through the tower taken on the line II—II of Fig. 1; Figs. 3 and 4 are enlarged fragmentary vertical sections through the lower part of the jacking structure taken on the lines III—III and IV—IV, respectively, of Fig. 2; and Fig. 5 is an enlarged plan view, partly broken away, of the gear reduction unit at the center of the jacking structure.

Referring to Fig. 1 of the drawings, the lower part of a conventional electric transmission tower is shown which is constructed of structural steel angle members. The tower has four legs, each of which has an upper section 1 that is spliced near the ground to a lower section 2. The lower section, sometimes called the stub,

2

is anchored in the ground. The tower tapers upwardly and has one or more cross arms (not shown) near its top for supporting electric transmission lines. The tower is shown as it appears after it has been raised several inches by means of the jacking structure that now will be described. Therefore, the lower ends of legs 1 are shown connected by horizontal girts 3 and diagonal braces 4 which were added after the upper sections of the legs were disconnected from the lower sections.

The jacking structure includes four jacks, A, B, C and D, one for each tower leg as shown in Fig. 2. The jacks are located outside of the tower and are connected rigidly together by braces so that the jacking structure surrounds the lower part of the tower. As shown in Figs. 1, 2 and 3, each jack includes a column or vertical frame having a pair of parallel vertical side rails 10 rigidly connected at their upper ends by a crossbeam 11, and rigidly connected at their lower ends by a hollow base member 12. The side rails are formed from angle bars pointing toward each other so that their side surfaces converge toward the center of the frame. The rails are connected at vertically spaced intervals by horizontal braces 13 that curve outward away from the rails. The lower part of the frame is further braced by a pair of tubular braces 14 welded to the base member 12 and converging upward and outward to one of the horizontal braces 13.

Located between the side rails of the frames is a pair of long parallel screws 16, the upper ends of which extend up through the crossbeam 35 at the top of the frame. Heads 17 are secured to the projecting upper ends of the screws, these heads being rotatably mounted in and supported by bearings 18 mounted on top of the beam. The screws are thus suspended in the frame from their upper ends. The lower end of each screw extends down into the hollow base member 12 where it splined in a worm gear 19 (jack A in Fig. 2) journaled in a box 21 mounted in the base member. Each gear meshes with a worm 22 on a shaft 23 that extends out through the front of the base member and through a bracket 24 attached to the top of that member. Between the base member and bracket, each shaft supports a bracket 26, around which a chain 27 extends. The outer end of one shaft may carry a hand wheel 28, by which the shaft can be turned if desired, whereupon the other shaft will be turned with it by means of the chain and sprockets, so that the two screws are

rotated in unison. The shaft 23 also extends out through the back of the base member for a purpose to be explained presently.

The base of each frame is designed to rest on top of a frame support formed from spaced inner and outer horizontal supporting beams 30 and 31. The frame is provided with a pair of depending lugs 32 (Fig. 3) that project down between the two supporting beams, where they are locked in place by removable pins 33 inserted through openings in the lugs, the inner channel beam 30, and a vertical plate 34 welded in the back of the outer I beam 31. The supporting beams are intended to be clamped to a leg stub 2 just below the splice. For this purpose 15 the inner beam is secured to an inclined clamping member 37 adapted to fit inside of a leg stub. The outer beam is provided with a similar clamping member 38 adapted to fit over the outside of the stub. The two clamping members are bolted to the stub between them before the jack frame is set on the frame support.

The actual lifting of each tower leg 1 is done by means of a lifting member 40 (Fig. 1) attached to the leg and to the screws 16 in the adjoining jack. When the screws are turned, the lifting member is moved vertically. The opposite ends of the lifting member are guided by the adjoining side rails 10 of the jack frame. The lifting member is attached to leg section 1 above the splice by means of a clamp 48 which is shaped to fit over the outer surface of the leg. This clamp is suspended from the lifting member.

After the four jacks have been mounted in place, as described in more detail in my copending patent application, the jack frames are rigidly connected together around the tower by means of horizontal girts 51 and inclined braces 52. Additional inclined braces 53 and horizontal diagonal braces 54 are added later, after certain interfering braces on the tower have been removed and the tower has been raised to the position shown in Fig. 1.

Before the tower is raised at all, the mechanism for operating the jacks A, B, C and D is installed. Thus, a horizontal frame 60 having upwardly extending ends 61 is suspended between a pair of the lowest girts 51 of the jacking structure by means of J bolts 62. The frame extends across the center of the jacking structure and tower. Mounted on the frame near its center is a gear reduction unit. As shown in Fig. 3, this unit includes a square housing 63 which is connected by bolts 64 to a pair of vertical plates 66 that extend above and below it. The lower ends of the plates are connected by bolts 67 to diagonal supporting members in frame 60. Rotatably mounted in the center of the housing is a vertical stub shaft 68 which carries a worm 69. This worm meshes with four worm gears 71 disposed with their axes horizontal and spaced at 90° intervals around the central worm, as shown in Fig. 5. Each worm gear is rigidly mounted on a short horizontal shaft 72, the inner end of which is journaled in a bearing 73 inside the housing, and the outer end of which is journaled in a bearing 74 mounted in a side wall of the housing. The four short shafts project from the four sides of the housing. The worm stub shaft 68 is driven by a motor 76 supported between the upper ends of the vertical plates 66 that support the gear housing. Any suitable motor may be used, but an air motor is preferred. Each of the worm gear shafts 72

is connected to a different one of the jack worm shafts 23 by means of a drive shaft extending diagonally of the tower. To facilitate installation and removal of these drive shafts, each one 5 is an expandable or telescoping shaft formed from a pair of axially-spaced shaft members 77 connected by a tubular member 78 splined on their adjacent ends. Setscrews 79 (Fig. 2) in the opposite ends of the tubular member engage the shaft members to hold them the desired distance apart. The opposite ends of each 10 of these drive shafts are coupled to the adjacent shafts 23 and 72 by means of flexible couplings 80.

It will be seen that when the motor is operated, the vertical worm 69 in gear housing 63 will drive all of the worm gears 71 therein in unison, and they in turn, through the diagonal drive shafts, will drive the jacks in unison. Therefore, all four corners of the tower are raised simultaneously until they reach the desired height. A tower extension, such as shown in my copending application, then is erected inside the jacking structure in the space between the leg stubs 2 and the bottom of the elevated tower to increase the height of the tower. After the extension has been erected, the jacks are operated to lower the lifting members 40 just enough to take the strain off the lifting clamps 48 so that they can be disconnected from leg sections 1. The jacking structure braces are removed next along with the jack drive, and then the jack frames are removed from their supports 30, 31. Following this, the frame supports are disconnected from the leg stubs and the excavations around the stubs are filled in.

According to the provisions of the patent statutes, I have explained the principle of my invention and have illustrated and described what 40 I now consider to represent its best embodiment. However, I desire to have it understood that, within the scope of the appended claims, the invention may be practiced otherwise than as specifically illustrated and described.

I claim:

1. The combination with a jacking structure adapted to surround a multiple leg tower and having a separate screw jack for each tower leg, of a separate substantially horizontal drive shaft for each jack extending toward the center of the jacking structure, a support suspended from opposite sides of the jacking structure and extending across it below the drive shafts, a gear housing mounted on said support near the center of said structure, a worm journaled on a vertical axis at the center of said housing, worm gears journaled on horizontal axes in the housing and meshing with said worm at uniformly spaced intervals around it, means for operatively connecting the worm gears with the inner ends of the drive shafts, and a motor for driving said worm.

2. The combination with a jacking structure adapted to surround a four leg tower and having a separate screw jack for each tower leg, of a separate substantially horizontal drive shaft for each jack extending diagonally toward the center of the jacking structure, a gear housing disposed near the center of said structure, a vertical worm journaled in the center of the housing, four worm gears journaled on horizontal axes in the housing and meshing with said worm ninety degrees apart, a stub shaft supporting each worm gear and driven by it, the 65 stub shafts extending out of the sides of the

housing in four different directions, a bearing supporting the inner end of each stub shaft inside the housing, means for operatively connecting the outer end of each stub shaft with the inner end of a drive shaft, and a motor for driving said worm, whereby all of said drive shafts are rotated in unison.

3. A jacking structure for a tower provided with four legs, said structure comprising a separate jack for each tower leg and braces for rigidly connecting the jacks together around the tower; each jack including a vertical frame, means connected to the lower end of the frame for supporting it, a vertical screw rotatably mounted at its upper end in the top of the frame and suspended therefrom, a driven gear mounted on the lower end of the screw for rotating it, a drive gear mounted on a horizontal axis for driving said driven gear, a drive shaft for the drive gear extending diagonally toward the center of the jacking structure, a lifting member threaded on the screw for vertical travel when the screw is turned, and means adapted to connect said lifting member to a tower leg; a support suspended from opposite sides of the jacking structure and extending across it below the drive shafts, a gear housing mounted on said support near the center of said structure, a vertical worm journaled in the center of the housing, four worm gears journaled on horizon-

10 15 20 25 30

tal axes in the housing and meshing with said worm ninety degrees apart, a stub shaft supporting each worm gear and driven by it, the stub shafts extending out of the sides of the housing in four different directions, a bearing supporting the inner end of each stub shaft inside the housing, means for operatively connecting the outer end of each stub shaft with the inner end of a drive shaft, and a motor for driving said worm, whereby after each leg has been separated into two sections at a point below the lifting member connected to it the upper sections of the four legs can be raised together.

4. Apparatus in accordance with claim 2, in which each of the drive shafts is a telescoping
